CLAIM

The ornamental design for a handle for a robotic vacuum cleaner, as shown and described.

DESCRIPTION

FIG. 1 is a front and right side perspective view of a handle for a robotic vacuum cleaner showing our new design in a lowered position;

FIG. 2 is a front and right side perspective view similar thereof, showing the handle in a raised position;

FIG. 3 is a right side elevational view of FIG. 1;

FIG. 4 is a right side elevational view of FIG. 3, showing the handle in a raised position;

FIG. 5 is a rear elevational view of FIG. 1;

FIG. 6 is a rear elevational view of FIG. 5, showing the handle in a raised position;

FIG. 7 is a top plan view of FIG. 1; and,

FIG. 8 is a top plan view, showing the handle in a raised position.

The details shown in broken lines in FIGS. 1-8 are for illustrative purposes only and form no part of the claimed design.
